UNITED STATES PATENT OFFICE.

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND.

SUPPORT FOR RING TRAVELERS.

Application filed January 16, 1928. Serial No. 247,018.

My invention relates to supports for circular ring travelers of the horizontal and reversible ring type adapted for use upon spinning and twisting frames, particularly 5 for dry twisting.

The lubricant for the traveler is necessarily deposited upon the inner face of the ring, and for that reason, when the thread leading from the delivery rolls to the spindle 10 is accidentally broken, the free end thereof strikes the lubricated inner adjacent face of the ring and soils not only the wound thread upon the spindle, but spots the thread wound upon adjacent spindles within the 15 radius of the thrashing thread end.

The essential objects of my invention are to make accidental soiling of the thread upon the spindle or spool impossible; to effect this end in a structure easy to assemble, composed 20 of a minimum of parts, and inexpensive to construct.

With the above purposes in view, my invention consists in such parts and in such combinations of parts as form the substance 25 of the claims hereto appended.

In the accompanying drawings which form a part of this invention, and wherein like reference characters indicate like parts, Figures 1 and 2 are a top plan view and 30 a side elevation respectively of a traveler support embodying my invention together with a traveler thereon,

Figure 3, a section of the same and of the adjacent portion of the ring rail taken on line 3—3 of Figure 1, and

Figure 4, a perspective view of the ring supporting and shielding member.

My device is herein shown mounted upon a ring rail 6 provided with the usual spindle 40 orifices 7, one only of which is herein indicated.

A member indicated in a general way by the reference numeral 9, adapted to perform the combined functions of a ring holder and a lubricant shield comprises a substantially circular base plate 10 with diametrically oppositely disposed lugs 12 provided with inclined open slots for the reception of screws or other attaching members 14. A central circular opening 16 in the plate is bounded by an integral vertical wall or shield portion 17. Annularly disposed in the base 10 of the member 9 are upwardly inclined tongues 19 formed from 50 the material of the base by radial and trans-

verse slits 20 and 21, the portions embraced by the slits being subsequently upwardly bent.

Resting upon the base is a horizontal spinning ring 23 comprising a lateral base flange 25, an intermediate body or web 26, and a flat laterally projecting operating head or flange 28. The free ends of the tongues 19 slightly overlap the flange 25 of the ring and clamp the latter tightly to the base plate 10. When thus fixed the tops of the ring 23 and the shield portion 17 are in substantially the same horizontal plane, with the edge of the latter slightly spaced from the flange 28 of the former, thus forming an annular recess 65 or running space 30 for the circular ring traveler 32.

The lubricant for the ring traveler is upon the inner face of the web portion 26 of the ring, and for this reason the shield portion 70 17 of the member 9 prevents access to the lubricated surface of a broken or loose string upon the spindle operating in the spindle orifice 7.

As shown clearly in Fig. 3, the upper edge 80 of the wall 17 terminates slightly below the upper edge of the spinning ring 23, and by such arrangement or structure the thread passing over the spinning ring is prevented from coming in contact with the upper edge 85 of the wall or guard 17, and there is thereby no chance of the thread becoming soiled from the lubricant which might possibly creep up the wall of the shield or guard and get on the upper edge thereof.

I claim:—

In a support for a ring traveler, a shield comprising a flat plate provided with a circular opening and a vertical cylindrical wall, integral with the plate around the opening, a plurality of inclined lips struck up from said plate annularly arranged upon the plate and spaced from the wall, a ring comprising a web, a flange upon the bottom of the web overlapped by the lips whereby the ring is securely held to the plate, and the flange upon the top of the web adapted to carry a traveler and disposed adjacent the upper end of the wall, the upper edge of the wall being below the upper edge of the ring, whereby contact of the thread with the upper edge of the wall is obviated.

In testimony whereof I have affixed my signature.

GEORGE H. GILLIGAN.
